UNITED STATES PATENT OFFICE.

EDWARD J. KUKAC, OF CHICAGO, ILLINOIS.

ADJUSTABLE MOLD.

Application filed February 18, 1921. Serial No. 446,019.

To all whom it may concern:

Be it known that I, EDWARD J. KUKAC, a citizen of the United States, residing at Chicago, in the county of Cook and State 5 of Illinois, have invented certain new and useful Improvements in Adjustable Molds, of which the following is a specification.

This invention relates to molds for casting cored bodies, and while not limited in 10 its application is designed primarily for embodiment in twin molds for casting two integrally united members, at least one of which is cored, as, for instance, a cored body member and its attaching shank with or 15 without coring.

The invention has for an object to provide simple and efficient means for varying the size of a cored mold to adapt it to produce different sizes of bodies, and to receive 20 and hold in proper position different sizes of cores appropriate to the several sizes of bodies for which it can be set. It has for a further object to incorporate these features of adjustment in a twin mold in a manner 25 to produce any of the several sizes of cored body portions in the same symmetrical or other predetermined relation to the integrally attached member, notwithstanding the variation in size of the cored body. It has for 30 a still further object to adapt the mold for casting variable sizes of bodies, either singly or in twin form, with the core permanently retained in the cored member and protruding therefrom, as, for instance, in 35 cases where the core embodies a construction in its protruding portion which is adapted to serve a useful purpose; for example, when an attaching leg is cast upon a binding post, connecting screw, conducting cable, or the 40 like.

The invention proceeds upon the principle of having a wall or walls of the adjustable portion of the mold not only movable to determine the size of body which will be 45 formed between them, but constructed to receive and support in proper position cores of different sizes, so that by adjusting the wall or walls until the space between them corresponds to the particular length of a core 50 that is to be subsequently removed from the casting, or the particular position of a core member that is to be embedded in the cast body, a body will be cast that will be appropriate in size to the particular core used, or 55 in other words, different sizes or characters of core can be made to assume proper rela-

tion to the body to be cast; the adjustable walls being recessed to receive the sustaining portion of the core, and the mold being divided in a plane intersecting the recesses 60 so that the core can be laid in the position which it is to have when the mold is closed thereon; and the core will constitute the closure for the recess or recesses that were formed to position it in the mold cavity. 65 When the mold is used for twin cast structures, or structures comprising a body with an integrally united shank or other member, and it is desired to have the cored body disposed symmetrically with relation to its integral part, two walls of the adjustable part 70 will be adjustable equally with relation to the cavity which forms the integral part.

In the accompanying drawing—

Figure 1 is a top view, and Figure 2 a 75 side view of a divided mold embodying the subject-matter of the present invention.

Figure 3 is a view of parts shown in Figures 1 and 2 opened out upon their hinging connection. 80

Figure 4 is a section on the line 4^x—4^x of Figure 2 looking in the direction of the arrow.

Figures 5 and 6 are detail views showing each a portion of the mold shown in Figure 3 85 with different forms of core member in position therein; and

Figure 7 is a view of a twin cored casting produced by the mold when equipped with a core such as shown in Figure 3. 90

1 and 2 represent two mold members hinged together at 3, adapted to be opened and closed and otherwise manipulated through the medium of handles 4. Mold members 1 and 2 are provided with complementary cavities 5 and 5^a, the side walls of which are preferably formed by fixed portions of the mold structure, while the end walls are formed of adjustable blocks 6, 6^a, 7, and 7^a, adapted to slide endwise in the cavity 100 and to be secured in any position of adjustment by means of screws 8 in slots 9. Blocks 6, 7, 6^a, and 7^a are formed with recesses 10, 11. These blocks separate in the same plane as that which divides the mold, and their 105 recesses 10, 11 are complementary so that when the mold is closed they form complete bores to receive the supporting ends 12 and 13 of a core member 14.

The core member is provided with shoulders 16 and 17 which serve as stops for the blocks 6, 7, 6^a and 7^a, and thereby limit the

adjustment of the blocks and regulate the length of the cavity. The core member 14 is typical of a number of core members of different sizes, and different shapes if desired, which may be placed in the holding recesses of the blocks, and which may determine the spacing of the blocks and therefore the size of the molded body appropriate to the core.

10 In addition to the molding space produced by the cavities 5, 5^a, the mold may have additional cavities 15, 15^a merging with the cavities 5, 5^a and of any suitable form, for instance, in the form of an annulus, the 15 inner wall of which is developed by the relief portions or projections 16, 16^a. 17, 17^a represent the complementary portions of the gate, and this gate preferably communicates with the mold space developed by the cavity ties 15, 15^a.

As suggested in Figure 5, the mold may be used to cast a head or attaching lug on a screw 18; as suggested in Figure 6 the mold is equally useful for casting such an attaching head or lug on the end of a conducting cable 19. When equipped with a core such as shown in Figures 3 and 4 the core completely closes the recesses in the end walls of the cavity. When used as suggested in Figures 5 and 6 some suitable means will be employed for closing the upper cavities of the mold, such, for instance, as the disk 20. When used as equipped in Figures 3 and 4, the article produced will be substantially that shown in Figure 7, in which both the integral members have openings therethrough. When used as equipped in Figures 5 and 6 the core members remain permanently with the casting as useful parts thereof.

I claim:

1. In a mold, the combination of walls separable to open the mold, a wall adjustable on said separable walls to vary the cavity space of the mold, said adjustable wall being divided and having its respective members independently and adjustably secured to and opened with said separable walls, and a core in the cavity of the mold recessed 45 into the meeting faces of said adjustable wall and released by the separation of the members thereof in the opening of the mold; said core having a shoulder engaging the members of the adjustable wall and positioning 50 them in their adjustment.

2. A divided mold comprising separable

members constructed with complementary cavities forming a molding space having walls defining said cavities provided with recesses, and a core resting on said walls in 60 the recesses thereof and positioned thereby in the molding space; a wall being adjustable to vary said molding space; and the core having a shoulder which engages the wall to limit the adjustment thereof. 65

3. A divided mold comprising separable members constructed with complementary cavities forming a molding space, walls defining said cavities being divided and having the meeting faces of their parts provided with recesses, and a core resting on said walls in the recesses thereof and positioned thereby in the molding space; both of said walls being adjustable to vary the molding space. 70

4. A divided mold comprising separable members constructed with complementary cavities forming a molding space, walls defining said cavities being divided and having the meeting faces of their parts provided with recesses, and a core resting on said walls in the recesses thereof and positioned thereby in the molding space; each of said walls having its parts connected to the respective mold members adjustable thereon to 80 vary the molding space; and said core having a shoulder in position to engage the parts of each wall and limit the adjustment thereof. 85

5. A divided mold constructed of members having complementary cavities, opposed walls in a cavity each provided with a recess adapted to receive and position one end of a core, and a connected cavity in a mold member adapted to mold a part projecting 90 integrally from the cast of the cavities first named; said walls being both adjustable to change the distance between them in symmetrical relation to the connected cavity. 95

6. A divided mold comprising members 100 constructed with complementary cavities each provided with a pair of end walls, the end walls of the respective cavities being complementary and providing complete end walls for the molding chamber developed by 105 said cavities; a wall of one cavity and the complementary wall of the other cavity being similarly adjustable to vary the dimensions of the mold space.

Signed at Chicago, Illinois, this 15th day 110 of February, 1921.

EDWARD J. KUKAC.
